TICKET SEVERING MEANS

Raymond T. Moloney, Chicago, Ill.

Original application April 2, 1935, Serial No. 14,314, now Patent No. 2,046,084, dated June 30, 1936. Divided and this application May 28, 1936, Serial No. 82,237

10 Claims. (Cl. 164—42)

This invention relates to a ticket band severing mechanism for a ticket dispensing or issuing device and the present application is a divisional application of my application Serial Number 14,314 filed April 2, 1935 for Ticket issuer for pin ball games, now Patent 2,046,084 granted June 30, 1936.

The improved ticket issuer and severing mechanism comprises in its preferred embodiment, a unit which may be, if desired, associated with an amusement game, of the pin ball type. The issuer is operated by an electric motor device, such as an electric motor, electromagnet, or a solenoid; and, such motor device may be made operative when motor switches are closed by the ball playing pieces. Such switches may be remotely located relative to the unit. In other situations, as in theatre ticket dispensers, only one motor switch need be provided with the motor device 10 operative whenever the switch is manually closed.

The illustrative type of unit to be herein disclosed embodies an electric motor having a shaft geared to drive another shaft carrying means to move to and fro, a dispenser member including 25 connections for turning a pin wheel in a step by step manner for moving a perforated ticket web to a dispensing position. It is for such organization that the severing mechanism of this invention is particularly provided.

30 The primary object of the invention is to provide an improved ticket severing mechanism for the ticket band dispenser.

Another object is to provide such severing mechanism operating automatically in timed relation to the movement of the ticket band so that the tickets will be accurately severed from the band.

Still another object is to provide a simple, fool-proof severing means, which will operate efficiently and not get out of order.

These and other objects are achieved by locating a knife in a position over the point of the ticket band where it is to be severed, said knife being spring pressed and normally held in inoperative position by a trigger means. A cam wheel or the like serves, in timed relation, with the rotation of a drive shaft, to cause release of the knife to severing position and also serves to 45 reset the knife, all as will later more fully appear.

In the accompanying sheets of drawings, illustrating the invention:

Figure 1 is a general plan view of the ticket dispenser unit including the improved severing means;

Figure 2 is a general side elevational view of the complete unit;

Figure 3 is a cross sectional view through the structure taken along the line 3—3 of Figure 1, looking in the direction of the arrows;

Figure 4 is a longitudinal sectional view through the ticket vender taken along the line 4—4, looking in the direction of the arrows;

Figure 5 is a face view of the cam wheel looking from the line 5—5 of Figure 3 in the direction indicated; and,

Figure 6 is a plan view of a portion of a web of tickets to be used with the unit.

For the sake of illustration, the dispenser unit is shown carried in a cabinet 10, having a front 15 wall 11 provided with an opening 12 for the discharge of the dispensed and severed tickets, said cabinet also having a horizontal floor 13 on which the unit is to be carried.

The unit includes a mounting plate 14 and the ticket web moving means comprises a wheel or drum 15, having pins 16' spaced angularly the proper distance apart. Said wheel is turnable on a horizontal transverse shaft 16 journaled in a bracket 17 mounted on the floor 13 or plate 14, as desired. The lower end of the wheel 15 projects downwardly through an opening formed in the floor 13 and plate 14 as shown in Figure 4, there being provided a lower cover plate 18 as shown, made fast to the under side of the floor 13. A web of tickets 19 is drawn from a source 30 of supply, not shown, and trained over the wheel 15, with the web formed at proper spaced intervals with pairs of holes 20 to fit over the pins 16' on the wheel.

Said web 19 is guided between the top side of the wheel 15 and a guide strip 21 which extends horizontally in the direction of the wall 11, as shown, there also being provided a lower complementary guide strip 22 so that the wheel 15 when turned step by step, as will later appear, serves to push the web between the strips 21, 22 to the point where the tickets are to be severed therefrom and be dispensed. Said strips 21, 22 are formed as part of, or carried by, a housing 23 which along one edge carries a vertical wall 24 including a right angularly bent end 25 delineating the terminal ends of the guide strips 21, 22. The wall 11 carries a discharge throat piece 26 including a ticket web deflector 27, the entrance to said throat 26 as shown in Figure 4, being arranged in spaced relation to the discharge end of the guide strips 21, 22. In the space thus provided, the knife later to be described operates when severing the ticket web. The manner of 50 55

driving the pin wheel 15 will next be described. A motor 28 of the electric type is mounted on the plate 14 to one side of the throat 26, said motor including a shaft 29 carrying a worm pinion 30 for driving a relatively large worm gear 31 carried fast on a transverse shaft 32 journaled in a bracket structure 33, as best appears in Figure 3. Said shaft 32 extends laterally in the direction of the housing 23 and at its terminal end 10 carries fast thereon a blank wheel 34, carrying an eccentric roller pin 35.

This pin or roller 35 as the wheel 34 turns is adapted to move into a vertical slot 36 formed in the upright wall portion 37 of a horizontal dis- 15 penser slide member 38. Said member 38 is movable to and fro in a guide 39 formed on the plate 14. This slide 38 carries a pin 40 to which is connected one end of a spring 41, the other end of which is connected to a pin and stop block 42 20 mounted on the plate 14 as shown in Figure 4. Said block 42 serves to limit the stroke of the slide 38 in one direction.

The wall 37 carries a pivot pin 43 for pivotally mounting one end of a link 44, the other end of 25 which is pivotally connected at 45 to the upper end of a crank arm 46 in turn pivotally mounted on the shaft 16 to rock a second arm 47 loose on the shaft 16. This arm 47 carries a pivotally mounted pawl 48 adapted when the link 44 is 30 pulled toward the wall 11, to engage a notch in a ratchet wheel 49 secured fast to the adjacent side of the drum wheel 16.

Thus, through the motor drive connections just described, the pawl 48 serves to turn the 35 ratchet wheel 49 one ticket length step at a time to turn the drum wheel 15 a like amount and thereby advance the ticket web a ticket length step at a time through the guide strips 21, 22 toward the throat 26. When the discharge end of 40 the web strikes the deflector 27 a ticket is in proper position in the space between the end of the guide strips 21, 22 and the throat entrance to be severed. A ticket severing means is provided to operate in timed relation to the movement of the web to sever the tickets at the said point described. Such severing mechanism will now be 45 described.

The wall 25 adjacent the housing 23 carries a pivot pin 50 for pivotally mounting a knife 51 disposed transversely over the ticket web when held 50 in operative position. The knife carries a pin 52 against which bears one leg of a relatively strong spring 53 mounted on the pin 50 as best shown in Figure 3. Said spring 53 has another leg stopped against a stop pin 54 mounted on the wall 25. The heel portion of the knife is formed with a trigger extension or boss 55 over which is engaged one end of a lever 56 pivoted intermediate of its ends by means of a pin 57 carried on the wall 25. The opposite end of said lever 56 rests on a horizontal pin 58 carried rigidly at the lower end of a vertical plate 59 in turn carried by means of guide pins 60 on the wall and slots 61 formed in the plate 59 so that the plate 59 is carried for up and down free movement on the wall 25. The lower end of this plate 59 rides on the periphery of a cam wheel 62 mounted fast on the shaft 32 to turn therewith, said cam wheel having a drop off notch 63 for a purpose presently to appear.

70 A stationary shear guide 64 is carried on the housing 23 to cooperate with the knife. This guide as shown in Figure 2 has an inclined edge which is engaged by the knife to "clear" the knife from the cut strip and prevent adhesion of the

knife and strip in the well known manner. The flush ends of the guide strips 21, 22 form a further stationary shear edge for cooperation with the movable knife 51. The mode of operation of the improved mechanism including the ticket severing means will now be described.

The ticket web is trained from a source of supply, not shown, over the pin wheel 15 as shown in Figure 4 with the web passed between the two guide strips 21, 22. When the circuit for the 10 motor 28 is closed as in Seiden et al. Patent No. 2,010,966 issued August 13, 1935, the same operates to turn the gearing 30, 31 to drive the shaft 32 and blank wheel 34. Thus the pin roller 35 enters the slot 36 to move the wall 37 and slide 38 15 from its starting position shown in Figure 4 to the right as appears in said figure, against the pull of the spring 41. Therefore, the link 44 is pulled to the right likewise, causing crank 46 and arm 47 to operate and through the pawl 48 push or turn 20 the ratchet wheel 49 one step. The web 19 always projects one ticket length into the throat 26 with the end thereof abutting the deflector 27.

The cam wheel 62 which also turns with the shaft 32 in the starting position of the parts is 25 so positioned that as soon as the wheel 62 turns to its release position the plate slide 59 drops off the high spot thereof into the notch 63 of said wheel. As seen in Figure 3, due to pressure of the spring 53 the lever 56 at its right hand end drops 30 with the plate 59 causing the left hand end of the lever 56 to raise and permit the trigger stop 55 also to raise. As a result the spring 53 rapidly snaps the knife lever 51 down through the ticket web so that the ticket projected into the throat 35 26 as described, is instantly severed. Such severed ticket then drops by gravity down the inclined bottom of the throat 26 to be dispensed through the opening 12 in the front wall 11 of the cabinet 10.

The motor in practice is only energized for an instant so that no sooner has it caused movement of the slide 38 it is dead again and the spring 41 is operative to restore the slide 38 to its starting position abutting the stop block 42. 45 The motor time of operation is controlled in practice so that the parts are always set in such position as properly to start the dispensing operation and the plate 59 is on the high spot of the cam wheel ready to drop into the notch 63 to 50 work the knife.

As the cam wheel 62 completes its revolution the plate 59 is wedged or cammed up to its raised position shown in Figure 3, causing the left hand end of the lever 56 as viewed in said figure to press 55 down on the extension 55 to lock the knife 51 in the raised position. Of course, this knife 51 is raised immediately it has operated by the action of the cam wheel so that the knife is out of the way by the time the pin wheel 15 has moved another ticket length of the web 19 against the deflector 27.

If desired the motor 28 can be held energized as long as desired by any appropriate switch and consequently the tickets may be dispensed and 65 severed as a continuous operation, the parts being so arranged that the dispensing or web moving operation is in timed relation to the severing operation.

It is the intention to cover all changes and 70 modifications of the illustrative example of the invention herein disclosed which do not in material respects constitute departures from the spirit and scope of the invention as covered in the appended claims.

What is claimed is:

1. In a ticket issuer, an electric motor operable when energized, a shaft driven by the motor, a cam wheel carried on and driven by the shaft, a reciprocable member operable by means driven from said shaft, a pin wheel driven from the reciprocable member for engaging a perforated band of tickets to advance the same across a guide surface to a point of discharge, a knife blade fulcrumed adjacent one end for pivotal movement and held in inoperative position adjacent the band, means engaging the knife blade to hold the knife in such position, said last mentioned means including a member engaging and controlled by the cam wheel to cause release of the knife blade for movement to operative position to sever a ticket from the band, and a spring operatively associated with the knife blade and engaging same to press it to severing position when released.
2. In a ticket issuer, an electric motor means including connections for operating a reciprocatory dispensing member, said issuer comprising a rotary wheel, guide means associated with the wheel to guide a ticket band over a portion of the wheel, said band and wheel having interlocking portions for causing positive advance of the band to a point of discharge, means operable from the reciprocatory dispensing member for rotating the wheel, the guide means terminating adjacent the discharge point for the tickets to be issued and including a stationary shear means, a movably mounted knife co-operable with said shear means to sever the tickets from the band, spring means directly engaging and urging said knife to cutting position, means engaging the knife to hold the same in an inoperative position, rotary means driven by the motor means in timed relation to the movement of the reciprocatory member, and a member engaging and controlled by said rotary means to release the knife holding means and cause the spring means to be operative and effect movement of the knife to cutting position.
3. In a ticket issuer, an electric motor having a shaft including connections for operating a slide member, said issuer comprising a rotary wheel, guide means associated with the wheel to guide a ticket band in engagement with the wheel and to a point of discharge, connections including a pawl and ratchet operable from the slide member to rotate the wheel to advance the band, the guide means terminating at the point of discharge and including stationary shear means, a spring pressed pivoted knife cooperable with said shear means to sever the tickets from said band, a member to hold the knife in inoperative position and means controlled from the motor shaft for causing release of the member to operate the knife in timed relation to the movement of the band.
4. In a ticket web dispenser comprising a guide along which a ticket web is moved, the combination therewith of a web severing mechanism comprising a frame, a spring pressed knife hinged to the frame on a horizontal axis in operative relation to the web, a lever pivotally mounted intermediate its ends on said frame and having one end arranged to engage and hold the knife in a raised position, a member mounted on the frame and guided thereon for free up and down movement, said member adjacent its lower end carrying means to engage the under side of the opposite end of said lever, and means comprising a motor driven device operable in timed relation with the movement of the web to allow the member to lower and cause the lever to swing on its axis to permit the knife to be pressed to web severing position and then to raise said member to swing said lever in an opposite direction to raise the knife and releasably lock it in inoperative position.
5. In a ticket web dispenser comprising a guide along which a ticket web is moved, the combination therewith of a web severing mechanism comprising a frame, a spring pressed knife hinged to the frame on a horizontal axis in operative relation to the web, a lever pivotally mounted intermediate its ends on said frame and having one end arranged to engage and hold the knife in a raised position, a member mounted on the frame and guided thereon for free up and down movement, said member adjacent its lower end carrying means to engage the under side of the opposite end of said lever, and a cam device operable in timed relation with the movement of the web to allow the member to lower and cause the lever to swing on its axis to permit the knife to be pressed to web severing position and then to raise said member to swing said lever in an opposite direction to raise the knife and releasably lock it in inoperative position.
6. In a ticket dispenser, a motor device, a dispenser member connected to the motor to be driven thereby, means operable by the member to move a ticket web to a point of discharge, the combination therewith of a ticket severing mechanism comprising a wall arranged adjacent the web, a spring pressed knife carried on the wall, a pivotally mounted member carried on the wall to hold the knife in inoperative position over the web where it is to be severed, and means driven by power derived from the motor device to engage and cause release of the member to free the knife for its movement to severing position with respect to the web.
7. In a ticket dispenser, a motor device, a dispenser member connected to the motor to be driven thereby, means operable by the member to move a ticket web to a point of discharge, the combination therewith of a ticket severing mechanism comprising a wall arranged adjacent the web, a spring pressed knife pivotally carried on the wall, a lever carried on the wall for releasably holding the knife in inoperative position over the web at the point where it is to be severed, and means driven by power derived from the motor device to release the lever to free the knife and cause movement thereof to sever the web.
8. In a ticket dispenser, a motor device, a dispenser member connected to the motor to be driven thereby, means operable by the member to move a ticket web to a point of discharge, the combination therewith of a ticket severing mechanism comprising a wall arranged adjacent the web, a spring pressed knife pivotally carried on the wall, a lever carried on the wall which at one end engages and releasably holds the knife in an inoperative position over the web at the point where it is to be severed, and means driven by power derived from the motor device to release the lever to cause movement of the knife to sever the web, said power driven means serving also after the knife has severed the band to restore the knife to its inoperative position.
9. In a ticket dispenser, an electric motor having a rotatable shaft, a second shaft disposed at a right angle to the motor shaft and driven therefrom, a slide operable by the turning of

the second shaft, dispensing means operable from the slide to advance a ticket web over a support step by step to a point of discharge, the combination therewith of a web severing mechanism comprising a wall adjacent the web, a spring pressed knife pivotally carried on the wall in an operative position relative to the web at the point where it is to be severed, a device on the wall for holding the knife in inoperative position, and means on said second shaft for releasing the device to cause the knife to operate, said last mentioned means also serving to restore the knife to its inoperative position.

10. In a ticket dispenser, an electric motor having a rotatable shaft, a second shaft disposed at a right angle to the motor shaft and driven therefrom, a slide operable by the turning of the second shaft, dispensing means operable

from the slide to advance a ticket web over a support step by step to a point of discharge, the combination therewith of a web severing mechanism comprising a wall adjacent the web, a spring pressed knife pivotally carried on the wall in an operative position relative to the web at the point where it is to be severed, a lever on the wall engaging the knife to hold it in inoperative position, a slide member on the wall also engaged by the lever, and a cam wheel having a step off notch carried on the second shaft for rotation therewith, said cam wheel engaging the slide member on the wall to cause release of the lever and operation of the knife, and said cam wheel also serving to restore the knife after it has operated to its inoperative position. 5 10 15

RAYMOND T. MOLONEY.
